FIG. 6.

UNITED STATES PATENT OFFICE.

HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 874,784.

Specification of Letters Patent.

Patented Dec. 24, 1907.

Application filed May 25, 1904. Serial No. 209,612.

To all whom it may concern:

Be it known that I, HENRY W. MERRITT, citizen of the United States, and resident of Syracuse, in the county of Onondaga and State of New York, have invented certain new and useful Improvements in Type-Writing Machines, of which the following is a specification.

My invention relates to typewriting machines and more especially to the manner in which the type bars are hung on the segment and also to the means for guiding and arresting the segment in its case shift motion.

One embodiment of my invention is illustrated in the accompanying drawings, in which

Figure 1 is a front view in transverse vertical section of a typewriting machine having my invention applied thereto, and with parts omitted; Fig. 2 is a plan view of the type bar segment and the means for guiding the same; Fig. 3 is a vertical longitudinal section through the machine; Fig. 4 is a plan view of a type bar; Fig. 5 is a longitudinal section through one of the hangers; Fig. 6 is a detail elevation of the means for guiding and arresting the segment at one side thereof, as seen from the back of the machine; Fig. 7 is a perspective view of a rail used for guiding the segment in my construction; and Fig. 8 is a detail side view of the roller separator.

Although some of the features of my invention are applicable to other sorts of machines, said invention is more especially applicable to front - strike typewriters and I have accordingly shown it as applied to the Monarch typewriter. The main frame of this machine comprises a base portion 1, from which rise posts 2, which support a top plate 3 on which is mounted a carriage (not shown) which has thereon a platen 4. Key levers 5 are pivoted at 6 to the main frame and are restored to normal position by springs 7. Sub-levers 8, pivoted to the key levers at 9, have slots 10 formed therein and are guided by a fixed rod 11. The construction is such that when the key is depressed the upper end of its sub-lever is moved toward the back of the machine. Each sub-lever, at its upper end, has pivoted thereto a link 12 which extends therefrom toward the front of the machine and is pivoted to a type bar. The type bars are pivotally mounted on a shiftable open segment 13.

The front face of the segment 13 is formed with a plurality of concentric steps, two such

steps 14 and 15 being shown in the present instance, the step 14 being back of and having a less radius than the step 15. A series of type bar hangers are mounted on the segment, one set of hangers being mounted on each step. In the present instance these hangers are secured to the front vertical faces of the steps, but some of the advantages of the present arrangement of type bar hangers could be attained by mounting said hangers in other ways. The hangers 16 which are mounted on the step 14 have the U-shaped outline best shown in Fig. 5, the lower part of the U forming substantially an elongated slot 17, through which extends the stem of a headed screw 18, which is threaded into the segment. The connection is such as to afford a radial adjustment of the hanger before the screw is fully tightened. The two arms of the hanger are connected by a rivet 19 and have near their outer ends conical openings for the reception of the conical trunnions 21 of a type bar 22, which carries on its outer end a lower case type 23 and an upper case type 24 (Fig. 3). The hangers are spaced farther apart near the ends of the segment than near the center, and those hangers which are near the ends of the segment have their arms spaced more widely apart, thus affording longer pivots to the type bars at and near the sides of the system, where there is a greater tendency of lateral deflection of the type bars, than near the center of the segment. The type bar bearings may be tightened by heading up the rivets 19 and the rivets also constitute binding means that prevent any separation of the hanger arms in the action of the machine. The hangers 25 which are mounted on the front step 15 of the segment, are spaced intermediate the hangers 16 of the back step, and each of the hangers 25 overlaps two of the back hangers. As is clearly shown in Fig. 1, the front hangers 25 are also U-shaped, but their arms are bent inward, as shown at 26', to permit of access with a screw-driver to the screws 18 of the back hangers. The construction is such that one of the hangers of the back set may be removed or adjusted without disturbing those of the front set. Each of the front hangers 25 is formed with the conical bearings 20 and has a rivet 19 that unites the arms in the same manner as the hangers 16, and each of said hangers 25 is secured to the segment by a headed screw 26 threaded into the segment.

As best shown in Fig. 3, each of the hangers

25 has its upper end projecting beyond the upper end of the adjacent hangers 16 and curved at 27 toward the back of the machine, so that the pivot points 20 of the hangers 25 stand a little in front of and a little nearer the center of the segment than the pivot points 20 of the adjacent hangers 16. I prefer to give the pivot points of the hanger 25 and the adjacent hangers 16 the relative positions shown in Fig. 3, in which the line joining the two pivot points substantially bisects the angle between a line drawn from one of said pivot points to the normal position of a type and a line drawn through that pivot point 15 and the printing point. Such a line would be perpendicular to the line drawn from the normal position of a type to the printing point. The parts being arranged in this manner, those type bars which are mounted on 20 the front hangers 25 will be swung in an arc of slightly less radius than those that are mounted on the hangers 16. The lower case type 23 which is connected to one of the front hangers, will swing in the arc 28 (Fig. 3) and 25 a lower case type which is connected to a hanger 16, will swing in the arc 29. When the type bars are in their normal position resting against the segmental pad 30, those types which are connected to hangers 25 will 30 lie at the same distance from the front of the machine as those that are connected to the hangers 16, so that the type will occupy almost exactly the same relative positions in the basket as they would if all of their pivot points 35 were in a segment of the same circle. Those type bars which are connected to the hangers 16 are curved goose-necked fashion, as shown at 31, so as to clear the ends of the hangers 25. The links 12 pass forward over the top of the 40 open segment and are pivoted to the type bars at 32, said links extending into slots 33 (Fig. 4) formed in the tops of the type bars. Washers 34 are placed beneath the heads of the screws 18, one washer being used for two 45 screws and being nearly cut in two, as shown at 35 (Fig. 1), so that when one of the hangers is removed or loosened, the washer will remain in position, but without exerting any force. Each of the screws 26 has a washer 36 which 50 is formed with an arm 37 from which an arm 38 extends laterally.

In an opening 39 in the end of the arm 37 is secured one end of a type bar restoring spring 40 (Fig. 3), the other end of which is secured at 41 to that type bar 22 which is mounted on the hanger 25. In an opening 42 at the end of the arm 38 is secured one end of a similar spring which is connected to the type bar 22 which is mounted on one of the 60 adjacent hangers 16. Thus each of the washers 36 serves as a holder for two returning springs, one for a type bar of each set.

The segment 13 is shiftable up and down to bring the upper or lower case types into 65 printing position by the means ordinarily

used in the Monarch machine, or by any suitable means which may be provided for the purpose such, for instance, as those shown in the patent to Jacob Felbel, No. 657,927, dated September 18th, 1900. I have provided novel means for guiding the segment in these shifting movements. Two posts or frame pieces 43 are rigidly mounted in the main frame and each of them has a rail 44 (Figs. 2 and 7) seated in a vertical slot in its 70 face. Each of the rails 44 has a race-way 45 formed therein. A headed pull screw 46 extends through an unthreaded opening in the post 43 and is threaded into the outside face of the rail 44 near the middle thereof, as 75 shown in Fig. 1. Two push screws 47 are threaded through the post 43 and bear against the outside face of the rail 44. These three screws afford any desired adjustment of the rail 44 in a direction toward and from 80 the end of the segment. Said rail is clamped in adjusted position by set screws 48 which extend at right angles to the screws 46 and 47 and are threaded into the post 43 and bear against the front edge of the rail 44. The 85 segment 13 is formed at its ends with race-ways 49, (Fig. 2) which coöperate with the race-ways in the rails 44, through anti-friction balls or rollers 50. In the present instance, I provide at each end of the segment, 90 four anti-friction rollers, two of said rollers having their axes at right angles to the axes of the other two, as indicated in Fig. 1. The rollers 50 are spaced apart and held in proper position, two of them near the top and the 95 other two near the bottom of the race-way, by a separator plate 51, which lies between the rail 44 and the end of the segment and which has formed therein holes 52 (Fig. 8) in 100 which the rollers play. The separator plate 105 51 has projecting from the back edge thereof two lugs 53, which are adapted to engage stop bars 54 and 55, adjustably mounted on the rear face of the post 43.

The horizontally adjustable stop bars 54 and 55 are the segment stops which limit the down and up motions respectively of the segment. These bars are horizontally disposed and are secured to the posts by headed screws 56 which pass through elongated slots 110 57 in said bars and are threaded into the post. These bars are guided in their horizontal adjustment and are held against rotation about the screws 56 by flanges 58 projecting from the post 43. The outer end of 115 each of the bars is bent to form a lug 60, between which and the post a screw-driver or other instrument may be inserted to move the bar outward. A lug 61 projecting from the back face of the segment 13, or a plate 120 secured thereto, has a notch 62 with oblique top and bottom sides 63, and the ends of the bars 54 and 55 are formed with oblique stop 125 faces 64 which coöperate with the oblique faces 63 to limit the movement of the seg- 130

ment. As will be readily understood, the adjustment of the bars 54 and 55 in a horizontal direction will regulate the up and down movement of the segment.

5. It will be perceived, more especially by an inspection of Figs. 1 and 3, that two consecutive hangers of the front set have their arms or branches close together and that the ends of these hangers lie in the path or plane of motion of one of the type bars of the rear set. Said type bar of the rear set is curved around the ends of the hangers of the front set and has the actuating link 12 applied thereto at a point 32 which lies on the side of the front hanger opposite to the pivot of the rear type bar. In other words, the rear type bar is curved about the end of the hanger of the front type bar in such fashion that said hanger is interposed between the pivot of the rear type bar and the point in said type bar at which the actuating link 12 is applied thereto. By thus placing the hangers of one set close together and arching the type bars of the other set over the ends of said hangers, the space in the segment is utilized to the best advantage, and I am enabled to use long pivots for the type bars. By an inspection of Fig. 3 it will also be perceived that the points 32 at which the actuating links 12 are applied to two consecutive type bars, and the pivots of those type bars all lie approximately in a plane which bisects the angle between the normal position and the printing position of one of said type bars.
35. Various changes in the details of construction and arrangements may be made without departing from my invention.

What I claim as new and desire to secure by Letters Patent, is:—

40. 1. In a front-strike typewriting machine, the combination of two bearing faces, one arranged forwardly of the other, two sets of type bar hangers, one set alone being mounted on each of said bearing faces and the hangers of the forward set extending upwardly and overlapping those of the rear set, and type bars pivoted to each set of hangers.
2. In a front-strike typewriting machine, the combination of a segment having its front face formed in two steps, one above and back of the other; a series of hangers secured to the upper or back step by screws; and a series of hangers secured to the lower or forward step and bent so as to permit of access to the screws of the other series of hangers.

3. In a typewriting machine, the combination of a segment having an integral stepped face, one step of said face being back of and of less radius than the other; and a series of hangers mounted on said steps in staggered arrangement, the forward series of hangers extending upwardly and radially past the hangers of the rearward series.

4. In a front-strike typewriting machine, the combination of a segment having a

stepped face, one step of said face being back of and of less radius than the other; a series of hangers mounted on said steps, the hangers on the front step having their pivot points nearer the center of the segment than those on the other step; and type bars pivoted to said hangers.

5. In a front-strike typewriting machine, the combination of a segment; a series of type bar hangers mounted thereon in a plurality of sets, the hangers of one set having their pivot points back of and farther from the center of the segment than those of the front set; type bars pivoted to said hangers, those type bars which are pivoted to the back set of hangers curving over the hangers of the front set; slots in the upper edges of said type bars; links pivoted to said type bars in said slots, and keys connected with said links.

6. In a front-strike typewriting machine, the combination of two upright sets of type bar hangers secured upon stepped bearing faces, the steps being at different distances from the printing point, the hangers of one set being mounted on the step which is nearest the printing point, the hangers of the other set being secured to the step farthest from the printing point, and said last mentioned set of hangers being longer than the first mentioned set and being also arranged to overlap said set and to extend upwardly and radially beyond the upper ends thereof.

7. In a typewriting machine, the combination of a type bar segment having concentric stepped bearing faces that extend substantially throughout the extent of the segment at the front face thereof, two sets of overlapping type bar hangers secured to said stepped bearing faces, the hangers on one bearing face extending in front of the other bearing face and of the hangers on said other bearing face, and type bars pivoted to said hangers.

8. In a typewriting machine, the combination of an upright type bar segment having integral concentric stepped bearing faces that are in different transverse planes fore and aft of the machine, two sets of individual overlapping type bar hangers, one set only being mounted on each step of the segment and having type bar bearings that are in different planes fore and aft of the machine and at different distances from the printing point, and type bars pivoted to said hangers.

9. In a typewriting machine, the combination of an upright type bar segment having concentric stepped bearing faces that are in different transverse planes fore and aft of the machine, two sets of individual overlapping type bar hangers secured to said stepped bearing faces of the segment, screws for securing said hangers in place, the screws of the rear set of hangers being accessible between the hangers of the front set, and type bars pivoted to said hangers.

10. In a typewriting machine, the combination of an upright type bar segment having concentric stepped bearing faces that are in different transverse planes fore and aft of the machine, two sets of individual overlapping type bar hangers secured by screws to said stepped bearing faces of the segment, the front set of hangers having contracted portions to afford access to the screws of the rear set of hangers, and type bars pivoted to said hangers. 5
11. In a typewriting machine, the combination of an upright open segment having concentric stepped bearing faces that are in different transverse planes fore and aft of the machine, a plurality of sets of overlapping staggered hangers secured to said stepped faces of the segment, the different sets of hangers having type bar bearings that are in different planes fore and aft of the machine and at different distances from the printing point, type bars pivoted to said hangers and key actuated links that extend over the open type bar segment and connect with the type bars. 15
12. In a typewriting machine, the combination of two sets of type bar hangers arranged in different planes, the front set of hangers having contracted portions to afford access to the fastening means of the hangers in the rear thereof. 20
13. In a typewriting machine, the combination of a segment having stepped bearing faces, a set of type bar hangers secured to each stepped bearing face, and type bars pivoted to the hangers at different distances from the printing point, all of the type bearing ends of the type bars being alined in the basket. 25
14. In a typewriting machine, the combination of a segment having stepped bearing faces, a set of type bar hangers secured to each stepped bearing face, the hangers of one set being staggered relatively to the hangers of the other set, and type bars pivoted to the hangers at different distances from the printing point, and the forward set of type bars being bent to clear the front set of hangers, all of the type bearing ends of the type bars being alined in the basket. 30
15. In a typewriting machine, the combination of a segment having stepped bearing faces, a set of radially adjustable type bar hangers secured to each stepped bearing face, and type bars pivoted to the hangers at different distances from the printing point and in different planes fore and aft of the machine, all of the type bearing ends of the type bars being alined in the basket. 35
16. In a typewriting machine, the combination of an upright type bar segment having concentric stepped bearing faces that are in different planes fore and aft of the machine, two sets of forked type bar hangers, one set being secured to each stepped bearing face, and staggered relatively to the hangers of the other set, a set of screws for each set of hangers, one set of screws being behind the other set and accessible from between the hangers of the front set, and type bars pivoted to the hangers, one set of bars being pivoted at a different distance from the printing point than the other set and in a different plane fore and aft of the machine and the type bearing ends of all the bars being alined in the basket. 40
17. In a typewriting machine, the combination of a shiftable segment having roller bearing guides therein, coöperating roller bearing guides, bearing rollers interposed between said guides, and means for effecting a relative adjustment of said guides, said adjusting means comprising a central pivotal screw that is effective to produce a bodily movement of one of said guides and individual adjusting screws near the ends of said guide and which act in opposition to said central or pivotal screw. 45
18. In a typewriting machine, the combination of a series of type bars pivoted to hangers in a plurality of rows; returning springs each connected at one end to a type-bar; and a series of fixed pieces to each of which is connected a plurality of said springs, the spring for one type bar of each row being connected to each of said fixed pieces. 50
19. In a front-strike typewriting machine, the combination of a segment; a series of hangers secured by screws to the front face of said segment in a plurality of rows, one row being in front of another; washers for the securing screws of the hangers of the front row; type bars pivoted to said hangers; and returning springs, each connected at one end to a type bar, and at the other end to one of said washers, all of said springs being connected to the washers of the front row of hangers. 55
20. In a typewriting machine, the combination of a stepped segment; a series of type bars; hangers for said type bars mounted on said segment, one set of said hangers on each of the steps, and the hangers on the front step overlapping those on a back step; screws securing said hangers to said segment; washers for the screws of a back step, one of such washers coöperating with a plurality of screws; washers for the screws of the front step; and returning springs for said type bars, all of said returning springs being connected to the washers of the front step. 60
21. In a typewriting machine, the combination of a shiftable segment having a race-way at the end thereof; a frame piece; a rail having a race-way which coöperates with the race-way at the end of the segment, said rail being adjustably connected 65

with said frame piece by pull and push screws; and anti-friction rollers in said race-ways.

22. In a typewriting machine, the combination of a shiftable segment having race-ways at the ends thereof; frame pieces; rails having race-ways which coöperate with the race-ways at the ends of the segment; each of said frame pieces having a screw passing therethrough and threaded into one of said rails; screws threaded through said frame pieces and engaging said rails; and anti-friction rollers in said race-ways.

23. In a typewriting machine, the combination of a shiftable segment having race-ways at the ends thereof; slotted frame pieces; rails seated in said slotted frame pieces and having race-ways which coöperate with the race-ways in the ends of the segment; pull and push screws for adjusting said rails in the slots; set screws for clamping said rails in adjusted position; and anti-friction rollers in said race-ways.

24. In a typewriting machine, the combination with a shiftable segment, of two coöperating race-ways, one of which is on the segment and the other of which is on the frame of the machine, one of said race-ways being in a rail which is adjustable by pull and push screws; and anti-friction rollers in said race-ways.

25. In a typewriting machine, the combination with a segment which is shiftable up and down, of stops for said segment, said stops having oblique stop surfaces and being adjustable horizontally.

26. In a typewriting machine, the combination with a shiftable segment, of segment stops consisting of slide-bars having oblique stop-faces.

27. In a typewriting machine, the combination with a segment which is shiftable up and down, of segment stops consisting of bars having oblique stop faces and adjustable in a horizontal direction; and means for guiding said bars and holding them in adjusted position.

28. In a typewriting machine, the combination of a shiftable segment; frame pieces having guides for said segment; and segment stops mounted on said frame pieces for adjustment toward and from said segment, said stops having oblique stop surfaces.

29. In a typewriting machine, the combination with a shiftable segment and frame pieces having guides for said segment, of segment stops consisting of bars mounted on said frame pieces and having oblique stop surfaces; said bars being guided by flanges on said frame pieces and connected to said frame pieces by screws which pass through slots in said bars.

30. In a front-strike typewriting machine, the combination of a series of type bars arranged in two sets, the type bars of one set

alternating with those of the other; a forked hanger for each of said type bars, said hangers arranged in two sets, the hangers of one set having their pivot points nearer to the front of the machine and nearer to the printing point than those of the other set, and the ends of the hangers of the front set lying in the planes of motion of the type bars of the rear set, and said type bars of the rear set being curved or formed to avoid interference with said hangers of the front set; and a segment to which said hangers are secured.

- type bar, said other type bar being curved about said end of said hanger in such fashion that said end of said hanger is interposed between the pivot of said type bar and the 5 point in said type bar at which its actuating means is applied to it.
35. In a typewriting machine, the combination of two front-strike type bars having overlapping pivots; actuating means for said 10 type bars, the points of application of said actuating means to said type bars and the pivots of said type bars all lying approximately in a plane that bisects the angle between the normal position and the printing 15 position of one of said type bars.
36. In a typewriting machine, the combination of a segment having stepped bearing faces; a series of front strike type bars arranged in two sets; a series of individual 20 hangers for said type bars, the hangers of each set being mounted on one of the steps of said segment; and actuating means for said type bars, the points of application of said actuating means to two consecutive 25 type bars and the pivots of said type bars all lying approximately in a plane that bisects the angle between the normal position and the printing position of one of said type bars.
- 30 37 In a typewriting machine, the combination of a segment having stepped bearing faces; a series of type bar hangers arranged in two sets, one mounted on each of said bearing faces; a series of type bars mounted 35 in said hangers; and actuating means for said type bars; the pivots of the type bars of one set overlapping those of the other set and so disposed that a line through two of said pivots would approximately bisect the 40 angle between the normal position and the printing position of one of said type bars, an end of the hanger of one type bar lying in the plane of motion of a type bar of the other set, said other type bar being curved about 45 said end of said hanger in such fashion that said end of said hanger is interposed between the pivot of said type bar and the point in said type bar at which its actuating means is applied to it.
- 50 38. In a typewriting machine, the combination of a segment having stepped bearing faces; a series of individual type bar hangers arranged in two sets, one set mounted on each of said bearing faces; a series of type 55 bars pivoted to said hangers; and actuating means for said type bars; a hanger of the first set having an end lying in the plane of motion of a type bar of the second set, said type bar being curved around said end of 60 said hanger and having its actuating means applied thereto on the side of said end of said hanger opposite to the pivot of said second type bar.
39. In a typewriting machine, the combination of a shiftable type bar segment; 65 frame pieces for supporting or guiding said segment, and provided with slots having rails set therein, roller bearings between said segment and said frame pieces, said roller bearings comprising a race-way in each end of the segment and an opposing race-way in each of said rails, and means for adjusting the two ends of each of said rails independently, the race-way in the rail at one end of the segment facing that in the rail at the other 70 end of the segment.
40. In a front-strike typewriting machine, the combination of a type bar segment having two bearing faces, one nearer the front of the machine than the other; two sets of type 80 bars of different lengths; and two sets of individual hangers in which said bars are pivoted, the hangers for the longer type bars being mounted on the rear bearing face of the segment and the hangers for the shorter type 85 bars on the forward bearing face and the pivots of the type bars being so arranged that the type bearing ends of said type bars are normally in alinement.
41. In a front-strike typewriting machine, 90 the combination of a type bar segment having two bearing faces, one nearer to the front of the machine than the other; two sets of type bars of different lengths, said type bars having long pivots; and individual hangers 95 for said type bars, the hangers for the shorter type bars being secured to the forward bearing face of the segment and said hangers standing in front of the hangers for the longer type bars, said hangers for the longer type 100 bars being secured to the rear bearing face of the segment.
42. In a front-strike typewriting machine, the combination of a type bar segment having two bearing faces, one nearer to the front 105 of the machine than the other, two sets of type bars of different lengths, said type bars having long pivots, and individual hangers for said type bars, the hangers for the shorter type bars being secured to the forward bearing 110 face of the segment and said hangers standing in front of the hangers for the longer type bars, said hangers for the longer type 115 bars being secured to the rear bearing face of the segment and the pivots of the type bars being so arranged that the type bar bearing ends of said type bars are normally in alinement.
43. In a front-strike typewriting machine, the combination of a stepped segment having bearing faces, one in front of the other; a single set of type bar hangers mounted on the rear bearing face; a single set of type bar hangers mounted on the front bearing face and extending upwardly and overlapping the 120 hangers on the rear bearing face; type bars pivoted in both sets of hangers; a set of securing screws for holding the rear set of hangers; and a separate set of securing screws for holding the front set of hangers, said sets 125 130

of screws engaging respectively with said front and rear bearing faces and the screws of one set alternating with those of the other.

44. In a front-strike typewriting machine, the combination of a segment having on its front side front and rear bearing faces, a single set of short hangers secured by a set of screws to the rear bearing face; a single set of longer hangers secured by a separate set of screws to the front bearing face, the longer hangers extending upwardly and overlapping the shorter hangers and having con-

tracted neck-portions between their ends where they pass the screws of the rear set of hangers so as to render said screws readily accessible. 15

Signed at Syracuse, in the county of Onondaga and State of New York, this 19th day of May A. D. 1904.

HENRY W. MERRITT.
